UNITED STATES PATENT OFFICE

LESTER W. SHELHAMER, OF OAK PARK, ILLINOIS, ASSIGNOR TO CAREY BRICK COMPANY, OF CHICAGO, ILLINOIS, A CORPORATION OF ILLINOIS

PROCESS OF BUILDING BRICK KILN ARCHES

Application filed March 5, 1931. Serial No. 520,296.

The present invention relates to brick kiln arches and the method of producing the same.

Among the objects of the invention is to provide a novel arch construction and a novel method of effecting the same. When bricks are piled with arches and then the pile or piles are lifted and conveyed to the kiln, there is a disturbance and displacement of the bricks, and a deformation of the arches. If the arches are produced by first setting the legs thereof and then building or setting the remainder of the piles, additional labor and time are required, and uniformity of the piles cannot be maintained.

Also when building wide arches, greater than the length of a brick, it has been impossible to close the arch with less than three upper layers of bricks without the breaking of the arch, which is very disadvantageous.

In the present invention the piles, without arches or arch portions, are built up completely in the general form of a rectangular parallelopiped, then, as such, transferred by suitable mechanical handling and setting mechanism, to the kiln and set down. Each successive pile is set down in given spaced relation to the previously set down pile. Then bricks of the two upper layers only, of the proximate piles, are displaced to close the arch therebetween. By this means and method arches of a width equal to the length of one and one-third, and one and one-half bricks may be closed with but two layers of bricks.

Referring to the drawings:

Fig. 1 is a side elevational view of a pile of green bricks on a car;

Fig. 2 is a similar view of two piles set down with a spacer;

Fig. 3 is a top plan view showing two proximate and spaced piles before displacing the arch forming bricks;

Fig. 4 is a similar view with some of the bricks in both upper rows of a pile displaced, and bricks filled in behind them;

Fig. 5 is a similar view with the arches closed and all filler bricks in place; and,

Fig. 6 is a view in side elevation of a completed arch between two piles of bricks.

Referring more in detail to the drawings, the invention is illustrated by the forming of piles of green bricks on a transferring means such as a car 1 at the moulding plant. The lower two layers of bricks 2, 3, 4 and 5 are laid end to end and side to side, with spaces 6 between the groups as is clearly shown in Fig. 1 of the drawings. At the ends of the piles, but two bricks 7 and 8 are lined up.

The third layer of bricks 9 are laid cross-wise of bricks 4, 5 and 8 of the second row. The fourth row of bricks 10 are laid cross-wise of bricks 9. The succeeding layers or rows are similarly laid, as is clearly shown in Fig. 1 of the drawings. Extra bricks 11, 12, 11^a and 12^a are placed on top of the piles to fill in spaces, as later described.

When the pile is completed, it is in the general form of a rectangular parallelopiped. When the pile has been transported on the car 1 to the kiln, a crane lowers a mechanical lifter, such as that described in Penfield's Patent No. 999,519 or Francis' Patent No. 859,445, and the lifting bars or fingers of the lifter are inserted in the spaces 6 at the bottom of the stack or pile of bricks. The crane then lifts the lifter with the stack of bricks, and conveys the same to the place in the kiln where the stack is to be set down. The lifting bars lift against bricks 9, and the mechanism in the bars, laterally press against the bricks of the lower two layers to prevent their falling out.

The stack is set down in the kiln, and if a previous stack has been set down, a spacer 13 is first placed against an end of the previously set stack, and the succeeding stack set down with an end thereof against the opposite side of the spacer.

The spacer 13 may be of any suitable construction, and may comprise walls 14 and 15 (see Fig. 2), adapted to lie adjacent the proximate ends of proximate stacks, and cross or tie members 16 for holding the walls 14 and 15 in proper relation.

After a pair of stacks have been thus set down, the spacer 13 is removed, and the workman displaces bricks from the two upper layers of the stacks. Bricks 17 and 18 are

turned from the positions shown thereof in Fig. 2 and moved out about one third or more of a brick length, as is clearly shown in Figs. 4 and 6. This forms a space 19 between bricks 17 and 18. The spaces behind bricks 17 and 18, are then filled in with bricks 11 and 12.

Bricks 20 and 21 are moved out over bricks 17 and 18, and close the gap 19, as is clearly shown in Figs. 4, 5 and 6. The spaces left behind bricks 20 and 21, are filled with bricks 11^a and 12^a.

Other stacks may be set down on the top of the stacks above described without reference to the position of the arches. It is not necessary to close the arches by upper stacks.

While I have herein described and on the drawings shown an illustrative embodiment of the invention and a method of producing the same, it is to be understood that the invention is not limited thereto but comprehends other arrangements, parts, details, features and process steps without departing from the spirit thereof.

Having thus disclosed the invention, I claim:

A process of building brick kiln arches comprising piling green bricks into rectangular piles with the bricks of each top layer arranged lengthwise of the pile and the bricks of each next lower layer disposed transversely of the pile, setting down two or more of said piles in longitudinally spaced relation, the space between each adjacent pair of piles being greater than the length of a brick, displacing transversely positioned bricks of the second from the top layers at positions adjoining said space, and turning the displaced bricks to positions disposed longitudinally of the piles with the end portions projected toward each other and overhanging said space, so as to form part of an arch, and then displacing longitudinally positioned bricks of the top layers to abutted positions overhanging the spaced apart ends of the first mentioned displaced bricks, so as to complete said arch, and finally filling the spaces between the other ends of the displaced bricks and the adjacent bricks of each pile by inserting additional transversely disposed bricks.

In witness whereof, I hereunto subscribe my name to this specification.

LESTER W. SHELHAMER.
